US0D1044568S

(12) **United States Design Patent** (10) Patent No.: **US D1,044,568 S**
(45) Date of Patent: ** Oct. 1, 2024

(54) **EARRING**

(71) Applicant: **SIRUS TANYA, LLC**, New York, NY (US)

(72) Inventor: **Sirus Tanyawattanakul**, Bangkok (TH)

(**) Term: **15 Years**

(21) Appl. No.: **35/518,710**

(22) Filed: **Jul. 11, 2023**

(80) **Hague Agreement Data**

Int. Filing Date: **Jul. 11, 2023**

Int. Reg. No.: **DM/232147**

Int. Reg. Date: **Jul. 11, 2023**

Int. Reg. Pub. Date: **Oct. 20, 2023**

(51) **LOC (14) Cl.** 11-01

(52) **U.S. Cl.**

USPC **D11/40**; D11/91

(58) **Field of Classification Search**

USPC ... D11/40-48, 1, 2, 3, 4, 16, 79, 80, 81, 86, D11/91, 92

Primary Examiner — Melanie Pellegrini

(57) **CLAIM**

The ornamental design for earring, as shown and described.

DESCRIPTION

1. Earring
2. Earring
- 1.1 : Top
- 1.2 : Bottom
- 1.3 : Left
- 1.4 : Right
- 1.5 : Front
- 1.6 : Back
- 1.7 : Perspective
- 2.1 : Top
- 2.2 : Bottom
- 2.3 : Left
- 2.4 : Right
- 2.5 : Front
- 2.6 : Back
- 2.7 : Perspective

1 Claim, 14 Drawing Sheets
